UNITED STATES PATENT OFFICE.

LOUIS L. ARNOLD, OF CHICAGO, ILLINOIS.

WINDOW-SASH.

SPECIFICATION forming part of Letters Patent No. 299,944, dated June 10, 1884.

Application filed July 17, 1883. (No model.)

To all whom it may concern:

Be it known that I, LOUIS L. ARNOLD, of Chicago, in the county of Cook and State of Illinois, have invented a new and Improved 5 Window-Sash, of which the following is a full, clear, and exact description.

The object of my invention is to provide a new and improved window-sash, which can easily be removed from the window-frame for 10 washing the panes, painting the sash, replacing the panes in the same, &c.

Reference is to be had to the accompanying drawings, forming part of this specification, in which similar letters of reference indicate corresponding parts in all the figures.

Figure 1 is a cross-sectional elevation of a window-frame provided with my improved sashes, showing them swung down. Fig. 2 is a front elevation of the upper sash, showing 20 parts of the same in longitudinal section. Fig. 3 is a sectional plan view of the frame, showing the manner in which the stop-beads and parting-strips are held in place.

The bottom sash, A, which is toward the 25 inside of the room, is pivoted at its lower end to the sash-frame by the pins E and the socket-plates F, and in the bottom of the grooves a thereof the sash-cords B are fastened, which cords then pass over pulleys C 30 in the sash-frame, and have weights secured on their outer ends in the usual manner. By removing the lower part of the stop-bead G the sash can be swung downward, as shown. The stop-bead G is provided on its inner surface, which rests against the side of the window-casing, with a staple, H, which is passed through a slot, H', into the casing. A pin or bolt, J, is then passed through the casing in such a manner that it also passes through the 35 staple H, passed through the aperture H', whereby the lower part of the stop-bead will be held in place on the window-casing.

The upper sash, K, is pivoted at its lower end to the lower ends of the side pieces of a U-shaped frame, L, which frame is composed of side pieces, l, and the top cross-piece, l', and is suspended from the sash ropes or cords B', which pass over pulleys C and have weights at the ends. The cords B' are secured to the 45 frame L at about one-third of the height of the frame from the upper ends of the shanks, and can be removed, as on the lower sash, A, by detaching the ropes. The sash K is provided in its top cross-piece, l', with a hook, M, 50 or analogous device, adapted to catch on a pin-

tle, N, projecting from the frame L, thus holding the sash in position within the frame L.

The cross-piece l' of the frame L may be so arranged with respect to the upper cross-bar of the sash K that the said cross-piece will be 60 hidden by the sash when the sash is in its normal position. If the upper sash, K, and its frame L, in which it is pivoted, are lowered, the upper sash, K, can be swung downward and toward the interior of the room, the 65 sash swinging on the pintles n, by which it is pivoted to the frame L. The bottom of sash K is recessed at P' to receive a casing, into which passes the pintle n. Check-studs may be used to prevent the said sash from swinging 70 down too far.

That the lower part of the parting-strip O may be removed, the parting-strip is provided with a staple, Q, which is passed through a slot or aperture in the window-casing, and 75 is so located that the pin J can pass through it, and thus hold it in place, in the same manner as it holds the lower part of the stop-bead G in place. By this construction the upper sash, K, can be readily turned down by removing the lower portions of the parting-strips O, its frame L held in position in the window-frame, and all binding of the sash in the frame prevented.

I am aware that it is not new in window- 85 sashes to lock the beads to the jambs by sliding bolts and staples, or to use grooved strips between the sash and window-frame, or to pivot the lower end of sash in an entirely inclosing slide-frame, or to pivot a sash to the 90 stiles, or to pivot a sash to side slats at the bottom and spring-latch it thereto at the top, or to hinge the lower section of a parting-bead and a sash so that the latter may be turned out; but

What I do claim as new and of my invention 95 is—

In a window-sash, the combination, with a window-frame, sash-cords B', and the removable parting-strips O, of the sliding frame 100 L, composed of the side pieces, l, and top cross-piece, l', and provided with the pintles n, and the sash K, having its side bars provided with the recesses P', to receive the pintles n, substantially as herein shown and described.

LOUIS L. ARNOLD.
